DANCING TAP AND TOE SUPPORT

Albert L. Sothen, Chicago, Ill.

Application September 13, 1933, Serial No. 689,306

3 Claims. (Cl. 36—8.3)

This invention relates to dancing taps and toe supports, and more particularly to tap plates provided for the toe parts of dancing shoes.

One of the main objects of this invention is to provide dancing taps which are adapted for wing step dancing, tap dancing and toe standing, and are also efficient in stiffening the sole and supporting the dancer's foot.

10 Another object is to provide a dancing tap
which is equipped with ears or similar rear por-
tions that extend a considerable distance rear-
wardly from the body part, almost to the instep
portion of the shoe or the bending portion of
the sole, so as to find especial adaptation for wing
15 step dancing, and also to provide the desired
rigidity and reinforcement to the sole of the shoe
and support for the foot, that when the dancer
engages in toe stands the foot is sufficiently sup-
ported.

20 A further object is to provide an efficient dancing tap and toe support which has considerable utility and is light, durable and inexpensive.

These and various other objects and advantages will become apparent from the following description, taken in connection with the accompanying drawings, in which the invention is shown in several preferred forms, it being understood that various other arrangements and forms of construction may be resorted to for carrying out the objects and purposes of this invention.

In the drawings:

Fig. 1 is a perspective view of a shoe showing one of the forms of my invention applied thereto.

Fig. 2 is a top plan view of said form of dancing tap.

Fig. 3 is a vertical cross-section thereof, taken on line 3—3 of Fig. 2.

Fig. 4 is a plan view of a modified form of dancing tap; Fig. 5 is a vertical section, taken on line 40 5-5 of Fig. 4; while Fig. 6 is a front elevational view thereof.

Fig. 7 is a plan view of another modified form of this invention; and Fig. 8 is a vertical section thereof, taken on line 8—8 of Fig. 7.

45 Fig. 9 is a plan view of a further modified form; and Fig. 10 is a vertical section thereof, taken on line 10—10 of Fig. 9.

Fig. 11 is a plan view of still another modified form of the invention; and Fig. 12 is a vertical section thereof, taken on line 12-12 of Fig. 11.

In the drawings I have shown my invention embodied in several of the various forms developed by me and extensively tested to determine and prove their utility and efficiency.

55. The particular form of dancing tap shown in

Figs. 1 to 3 inclusive, comprises a body part 20 which is constructed to conform to the shape of the forward part of the sole 21 of the shoe 22, and is arranged to be secured therebeneath; as for example, by providing apertures 23 in said body part to extend suitable fastening elements therethrough into the sole.

The body part in this form is made comparatively long so as to have its rear end 24 extend substantially to the flexing or bending portion 21' of the sole, and to be positioned adjacent the instep portion 22' of the shoe thereabove, in order that the connected forward part of the shoe sole will be fully stiffened and yet the shoe may be readily bent or flexed at the instep portion as may be required. Said rear end 24 is preferably indented or curved inwardly at its intermediate part, thereby providing a pair of rearwardly extending side ears or wings 25 and 25' outward of said indentation. 75

In this form the body part 20 is provided with a peripheral upstanding flange 26 which extends along the front toe portion thereof, and further extends entirely along both sides to the rear end of said body part, forming complete side flanges 26'. This flange is integral with the body part and arises therefrom for the thickness of the shoe sole or the height of its outer edge. Said flange, throughout its entire length, bears snugly against the edge of the sole and covers it, substantially as indicated in the drawings. 80 85

The body part 20 therein has its central portion cut away to leave an opening 27, thereby reducing the weight of the tap, and furthermore modifying the sound effect thereof. This opening 27 acts substantially in the nature of a sound opening on a sound box, and adds a resounding effect to the tap. 90

The form of tap shown in Figs. 4 to 6 inclusive, comprises a body part 30 which is shaped in conformity with the forward part of the sole of a shoe, and has openings 33 to receive suitable fastening elements for securing it underneath the sole. It is somewhat shorter than the body part of the preceding form, and its rear edge 34 is deeply indented or curved inward at its intermediate part, so as to provide a pair of relatively long side ears or wings 35 and 35' extending a substantial distance rearwardly from the two rear ends of the body part. 95 100 105

The distinctive feature of these prominent ears or wings is that they enable the dancer to produce clearly and distinctively the right and left wing steps during the dancing performance, and with very little effort and expenditure of energy. 110

In this form the body part 30 is provided with an integral upstanding flange 36 which extends only along the front of the toe portion 37 thereof. It arises substantially for the height of the shoe 5 sole, having its upper edge about even with the top of the sole and snugly clasping or bearing against the front edge. This form is thus rendered comparatively light and very efficient for use in tap dancing as well as in wing step dancing.

The form of tap shown in Figs. 9 and 10 comprises a body part 40 conforming to the forward part of the sole of the shoe, and being positioned substantially under the toe part thereof. Apertures 43 are provided therein for receiving suitable elements to secure the tap underneath the sole. The rear edge 44 of the body part is indented to form a pair of rearwardly extending side ears or wings 45 and 45'.

This form has an integral upstanding flange 46 at the front of its toe part, which extends for substantially the thickness of the shoe sole. It is relatively thick at the front or central portion and has a substantially flat front face 47 thereon, whereby this tap is essentially adapted for the shoes of dancers who perform toe stands, as well as for doing tap dancing. With this form the dancer has proper balance and complete control of his body while performing these exhibitions.

The form of tap shown in Figs. 11 and 12 comprises a body part 50 constructed to conform to the shape of the forward part of the shoe sole, and is provided with openings 53 for receiving suitable securing elements to fasten it under the sole.

The body part in this form is made comparatively long so that its rear end 54 extends substantially to the instep portion of the shoe or the flexing portion of the sole, to properly stiffen the sole and yet permit the desired flexing at the instep portion, in a manner similar to that described regarding body part 20 shown in Fig. 2. Its rear edge is indented at the intermediate part to form a pair of rearwardly extending side ears or wings 55 and 55'.

An upstanding flange 56 is provided at the front or toe portion on this body part 50, and arises substantially for the height of the sole and to bear snugly against the same, substantially as in the preceding forms, the top of the flange being also substantially level with the top of the sole.

The body part 50 herein also has its central portion cut away to leave an opening 57, thereby reducing the weight of the tap, and furthermore producing a modified sound effect, substantially as in the form illustrated in Fig. 2.

The form of this invention illustrated in Figs. 7 and 8 is adapted for tap dancing and is also particularly adapted as a toe protector for use on children's or kiddies' shoes, which are relatively broad at the toe part. They are provided

in pairs, one being for the right and the other for the left shoe; and they are especially effective in preventing the breaking and tearing of the toe part of the sole and also of the upper of the shoe. Each tap comprises a body part 60 adapted to fit under the toe portion of the sole of the shoe, and having openings 61 therein for receiving fastening elements 62 to extend into the shoe sole 63 for securing the device underneath the sole. Its rear edge 64 is indented centrally, thereby providing rearwardly extending ears or wings 65 and 65'; and an integral flange 66 extends upwardly from the front or toe part thereof to substantially the height of the sole of the shoe and to bear firmly against the same.

These members are adapted for shoes of children, both as dancing taps and as toe protectors; and are also adapted for the shoes of ball players and golfers, to protect the forward part of the upper and the sole, finding especial utility for pitchers when pitching ball and for golfers when making a drive, as they prevent the ground from coming in contact with the toe part of the upper and thus protect it as well as the sole of the shoe.

I claim:

1. A dancing tap comprising a body part conforming to the shape of and adapted to be secured under the forward part of the sole of a shoe, and a vertically upstanding integral flange 105 curved in conformity with and engaging the front end of the shoe sole, the front part of said flange having a substantially vertical flat face provided thereon, for performing toe stands.

2. A dancing tap of light metal comprising a 110 body part conforming to the shape of and adapted to be secured under the toe part of the sole of a shoe, and an integral relatively thick flange at the front of said body part extending upwardly substantially the thickness of the sole 115 and bearing against its front edge, the front part of said flange having a substantially flat vertical face provided thereon, for performing toe stands.

3. A dancing tap comprising a body part adapted to conform to the shape of and be secured under the front part of the sole of a dancing shoe, and having an integral peripheral flange extending around the front and the sides thereof, the main part of which extends upwardly for substantially the thickness of the sole 125 and clasps its front edge, and a pair of relatively long side wings extending rearwardly on said body part, providing an indentation therebetween extending a substantial distance toward the toe end, said wings extending substantially to 130 the ball part of the toes, thereby adapting this tap especially for wing step dancing in addition to tap dancing.

ALBERT L. SOTHEN.
